UNITED STATES PATENT OFFICE

154,918

DESIGN FOR A TEXTILE FABRIC

Adolphe Grivin, New York, N. Y.

Application October 29, 1948, Serial No. 149,388

Term of patent 3½ years

(Cl. D92—1)

To all whom it may concern:

Be it known that I, Adolphe Grivin, a citizen of the United States of America, residing in New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The design unit is contained within the dot and dash lines, which unit is repeated in regular succession as indicated by the extensions beyond the unit boundaries.

I claim:

The ornamental design for a textile fabric, substantially as shown and described.

ADOLPHE GRIVIN.
